UNITED STATES PATENT OFFICE.

FRANK B. LOCKTON, OF PEARL RIVER, NEW YORK, ASSIGNOR TO DEXTER FOLDER COMPANY, OF PEARL RIVER, NEW YORK, A CORPORATION OF NEW YORK.

PAPER-FEEDING MACHINE.

1,165,521.

Specification of Letters Patent.

Patented Dec. 28, 1915.

Application filed October 16, 1914. Serial No. 866,957.

To all whom it may concern:

Be it known that I, FRANK B. LOCKTON, a citizen of the United States, and resident of Pearl River, in the county of Rockland 5 and State of New York, have invented certain new and useful Improvements in Paper-Feeding Machines, of which the following is a full and clear specification.

This invention relates to feeding machines 10 in which sheet-engaging instrumentalities such for example as combing wheels, are periodically moved into and out of engagement with the top sheet of a pile for the purpose of imparting simultaneous feeding 15 movements of different magnitudes to a number of the sheets of said pile, the uppermost sheet being subjected to the greatest amount of displacement and those below it being displaced in lesser degrees in gradation 20 according to their position relatively to the top. The sheets of a pile are thus separated in a simple and efficient manner. It has already been provided for in the application of Talbot C. Dexter, Serial Number 25 795,486 to regulate the sheet-feeding action by an automatic regulation of the pressure exerted by the tail drag upon a pile of sheets, such pressure being governed by the period of activity of the sheet combing 30 instrumentality.

The primary object of the present invention is to provide improved means for regulating the sheet-feeding action by regulating the pressure exerted by the sheet-feeding 35 instrumentality in connection with suitable and efficient means for terminating the action of said sheet-feeding instrumentality.

Various constructions, combinations, and arrangements of parts will be found among 40 the other objects of the present invention, reference being had to the claims in connection with the accompanying drawings in which,—

Figure 1 is a top plan view of a sheet-feeding machine constructed in accordance 45 with the principles of the present invention, parts being broken away; Fig. 2 is a section on an enlarged scale on the line II—II, Fig. 1, parts being broken away; Fig. 3 is a section similar to Fig. 2 with the parts in different positions; Fig. 4 is a section similar to Fig. 2, showing the positions of the parts after the sheet-actuated mechanism has been tripped; Fig. 5 is a top plan view on

an enlarged scale of one side of the machine, 55 parts being broken away and parts shown in section; Fig. 6 is a section on the line VI—VI, Fig. 5; and, Fig. 7 is a fragmentary top plan view of the sheet-actuated pendulum mechanism. 60

In the embodiment shown in the drawings, the sheets of the pile P are retained along their forward edges by a vertical guard 1 with forwardly extending extremities 2 which permit a graded displacement 65 of the sheets near the top as shown in Figs. 2 and 4. The machine as a whole is best shown in Fig. 1 in which a shaft 3 is mounted in the side frames 4 and 5.

Journalized upon the shaft 3 are sleeves 6 70 and 7, each of which is provided with rearwardly extending arms 8. In the forward ends of said arms are journalized comber spindles 9 to each of which is keyed a combing wheel 10. As shown best in Fig. 5, each 75 of the comber spindles 9 has also keyed thereto a sprocket 11 over which runs a chain 12 for delivering power to said comber spindle 9 from another sprocket 13 (see Figs. 3 and 4) keyed to the shaft 3. Power 80 may be delivered to the shaft 3 by any suitable means not specifically concerned in the present invention.

Each of the sleeves 6 is withheld against longitudinal displacement on the shaft 3 by 85 means of collars 14 which are secured to the shaft 3 on the inner ends of said sleeves. As shown in Fig. 6, the right hand arm 8 on the sleeve 6 carries an outwardly presented lug 15 which under certain conditions is 90 adapted to be engaged by a lug 16 carried by the hub 17 of a lever provided with an upwardly extending arm 18 and a depending arm 19. A spring rod 20 which is slidably mounted in the eye-bolt 21 has its forward end pivotally connected at 22 with the depending arm 19. A spring 23 is interposed between the eye-bolt 21 and a collar 24 which is secured to the spring rod 20, thus providing a resilient pressure tending to 100 force the depending arm 19 rearwardly. As shown in Fig. 6, the arm 18 carries a pin 25 which projects in opposite directions on either side of the outer end of said arm. Journalized upon a pin 26 (see Fig. 3) carried by the side frame 5, is a bell crank lever with one arm 27 normally disposed horizontally and provided with a cut-out portion 28

which is adapted to engage the outer end of the pin 25 carried by the lever arm 18 and a depending arm 29.

A spring rod 30 having its lower end 5 journaled upon a pin 31 projecting laterally from the arm 27 of the bell crank lever, carries a collar 32 between which and an abutment 33 projecting from the side frame 5 is disposed a spring 34 which normally retains 10 the arm 27 in engagement with pin 25.

A connecting rod 35 has its rear end connected at 36 to the depending arm 29, its forward end being connected at 37 to an upwardly presented arm 38 which is carried 15 by a sleeve 39 (see Figs. 3, 4 and 7). Forwardly presented arms 40 which are carried by the sleeve 39 serve to journal a shaft 41 which carries at one end, a pawl 42 which as shown best in Fig. 2, is adapted at certain 20 times to be thrown into engagement with a ratchet 43 keyed to the shaft 4, said shaft being preferably that on which the feed rollers 45 are mounted.

Intermediately of the arms 40, the shaft 25 41 carries a pendulum 46 which is adapted at certain periodic intervals to be actuated by a sheet passing from the pile P and which by its displacement, operates to throw the pawl 42 into the ratchet 43. The combined 30 gravity effect of pawl 42 and pendulum 46 tends to hold said pawl and pendulum in the position shown in Fig. 2 and in full lines in Fig. 4. According to the present invention, whenever during the feeding movement of 35 the top sheet of a pile, the sheet next underlying it is not forced forwardly into a position from which the next normal feeding operation would ordinarily present it to the front gages of the machine which is to receive the sheet, suitable and efficient means are provided for rendering the feeding action more intense so as to make up its lack of forward movement. For this purpose, a reference to Figs. 2, 3 and 5 will show that 40 the forwardly presented ends 2 of the guide bars 1, are provided with openings 47. When a sheet covers said openings, the roller 48 mounted at the lower end of a lever arm 49 will be prevented from entering 45 said openings. On the other hand if a sheet has not been moved a sufficient distance to cover said opening, the rollers 48 will enter the opening 47 and cause a downward displacement of the arm 49, unless the cam 50 mechanism presently to be described, retains 55 said arm against displacement. Said arm is keyed to a shaft 50 which extends transversely of the machine. Keyed to said shaft on opposite sides are bell crank levers 51, 60 each provided with a cam arm 52. Each of the cam arms has journaled thereon a cam roller 53 which runs on a cam 54, said cam 54 being keyed to a cam shaft 55.

Rigid with the arm 52 is another arm 56 65 which carries at its upper end a cam roller

57, said cam roller having running contact with the upper surface of a detent 58, which is carried by a shaft 59, and as shown in Fig. 5, said shaft 59 is provided with a spring 60 tending at all times to move the 70 detent 58 upwardly. Said detent is normally adapted at certain times to positively engage an angle arm 61 which is secured to the forward end of a plunger 62, said plunger being reciprocably mounted in a suitable 75 bearing lug 63 and a bracket 64. A collar 65 mounted on said plunger serves to confine a compression spring 66 between it and the bearing lug 63, thus imparting a constant tendency to force the plunger 62 rearwardly. 80 The rear end 66 of said plunger is enlarged to adapt it to engage a laterally projecting pin 67 carried by a lever arm 68 which projects upwardly from the sleeve 6, the result being that whenever the detent 58 releases 85 the lever arm 61, the spring 66 forces the plunger 62 against the pin 67 and adds its pressure to the weight of the combing wheel, thus causing said combing wheel to engage the top sheet of a pile with added pressure. 90 Under normal working conditions however, the plunger 62 is retained against this action, the comber wheel 10 being raised by a cam 69 which engages a cam roller 70 journaled on the forward end of a cam rod 71, 95 the rear end of said cam rod being journaled upon the pin 67.

As shown in Fig. 4, a finger cam 72 is keyed to the cam shaft 55 and is properly disposed thereon to adapt it to engage a 100 roller 73 which is journaled on a cam bar 74, the rear end of said cam bar being provided with branches 75 which straddle the cam shaft 55 and serve to support said cam bar. The rear end of said cam bar is journaled 105 upon the pin 25 carried by the lever arm 18 (see Figs. 4 and 6). Drop rollers 76 are provided, but inasmuch as they have no specific bearing upon the present invention, means for raising and lowering the same 110 have not been shown on the drawings.

The operation of my improved machine will now be readily understood and briefly described as follows: As shown in Fig. 1, it will be understood that the combing 115 mechanism is duplicated on opposite sides of the machine, so that whenever the forward edge of a sheet which is being fed from the pile P, comes into contact with the pendulum 46 on one side before it does 120 on the other, the movement of one edge of the sheet will be retarded and come to a standstill before that of the other edge of the sheet, thus serving to straighten the sheet. Referring to Fig. 2 when the machine is acting normally, *i. e.*, when after each top sheet is fed off, the sheet therebelow will occupy the position shown in Fig. 2, the cam 69 traveling in the direction of the arrow, permits the cam roller 125

70 to move forwardly. Immediately the combing wheel 10 drops by its own weight to the pile. The then top sheet thus engaged by the comber is moved forwardly 5 until it strikes the pendulum 46. As soon as this occurs shaft 41 is oscillated to throw the pawl 42 into engagement with the ratchet 43, the result being that the rapidly moving ratchet kicks the pawl 42 upwardly 10 and oscillates the sleeve 39 by throwing the arms 40 into the position shown in full lines in Fig. 4. The pawl 42 and pendulum 46 then assume the full line position shown in Fig. 4, pawl 42 having been disengaged 15 from the ratchet 43 by the momentum imparted thereto by said ratchet. This movement is accompanied by a rearward movement of the arm 38 and connecting rod 35 which in turn operates the bell crank lever 20 arm 29 to throw the lever arm 27 into elevated position shown in Fig. 4 against the pressure of the spring 34. As a consequence, lever arm 27 is disengaged from the pin 25, whereupon the pressure of spring 23 acting 25 upon the arm 19 at once raises the combing wheel 10 from the paper, thus terminating the combing action. Let it be supposed, however, that during the preceding combing action the next top sheet was left 30 in the position shown in Fig. 3. Under these conditions, during the time that the roller 70 travels over the outer run of the cam 69, the pin 67 being in abutment with the plunger 62 overcomes the pressure of the 35 spring 66. At the same time, the detent 58 is retained in the position shown in Fig. 2 by means of the spring 60 shown in Fig. 5. Shortly before the cam 69 reaches a position in which the cam roller 70 travels to 40 the inner run of said cam, the cam roller 53 drops into the hollow in the cam 54, thus permitting the arm 49 to drop as shown in Fig. 3. The consequence of this action is that the cam roller 57 is permitted to depress the detent 58, so that as the cam roller 70 drops down to the inner run of the cam 69, the combing wheel 10 moves downwardly to the paper under the pressure of the spring 66, as well as under its own 45 weight. The result is that an additional pressure is thus applied to the combing action which produces a more rapid movement of the top sheet until it strikes the pendulum 46 when the lever arm 27 is displaced upwardly and releases the spring 23 50 in the manner already pointed out. As a result, the arm 19 throws the lug 16 upwardly into engagement with the lug 15 carried by the sleeve 6, and inasmuch as 55 the tension in the spring 23 is greater than the tension in the spring 66, the combing wheel 10 is forced upwardly in the manner pointed out. After this operation has taken place, the finger cam 72 eventually comes 60 into engagement with the cam roller 73 and

by forcing the pin 25 in a clockwise direction around the shaft 3, eventually permits the spring 34 to force the lever arm 27 downwardly so as to latch the lever arm 18 in the position shown in Figs. 2 and 3. 70

It will be understood that various modifications and changes may be made in the general construction and arrangement of parts for applying an additional pressure to the combing wheel in order to facilitate 75 the movements of the sheets, so I do not wish to be limited to the specific construction shown on the drawings.

I claim:

1. In a sheet feeding machine, the combination with a sheet feeding instrumentality adapted to exert a normally constant pressure on the top sheet of a pile, of means for applying additional pressure to said instrumentality, including an element adapted to 80 operate by gravity to throw said additional pressure means into action, said element being suitably disposed to be sustained in inoperative position by said top sheet when normally fed by said sheet feeding instrumentality.

2. In a feeding machine, the combination with a feeding instrumentality adapted to exert a normally constant pressure on the top sheet of a pile, of periodically operated 95 means for applying additional pressure to said instrumentality during its action said means being adapted to be rendered inoperative by said sheet if said sheet has reached a predetermined point in its travel. 100

3. In a feeding machine, the combination with a feeding instrumentality adapted to exert a normally constant pressure, of means for applying additional pressure to said instrumentality, said means being controlled by the position of the top sheet on the pile. 105

4. In a feeding machine, the combination with a sheet feeding instrumentality adapted to exert a normal feeding pressure upon 110 the top sheet of a pile of means controlled by the position of said sheet for applying additional pressure to said instrumentality prior to the action of said instrumentality on the sheet.

5. In a feeding machine, the combination with a sheet feeding instrumentality adapted to exert a normal feeding pressure upon the top sheet of a pile, of means controlled by the position of said sheet for applying 115 additional pressure to said instrumentality prior to and during its action on the sheet.

6. In a sheet feeding machine, the combination of a combing wheel normally adapted to apply a substantially constant pressure to the top sheet of a pile, of sheet controlled means for intermittently applying additional pressure to said combing wheel. 125

7. In a feeding machine, the combination with a sheet combing instrumentality, of 130

means for automatically changing the pressure exerted by said instrumentality including a gravity-operated element suitably disposed to be sustained in inoperative position by a sheet normally fed by said instrumentality.

8. In a sheet feeding machine, the combination with an automatically controlled sheet separating device, of sheet controlled means for varying the pressure of said device.

9. In a sheet feeding machine, the combination with an automatically controlled sheet separating device, of sheet controlled means for varying the pressure of said device, said means being automatically operated to modify the velocity of feed of the top sheet of a pile.

10. In a sheet feeding machine, the combination with a sheet-actuated pendulum and a sheet combing device, the combing period of which is controlled by said pendulum, of sheet controlled means for regulating the pressure on said sheet combing device.

11. In a sheet-feeding machine, the combination of a sheet-combing device movable into and out of engagement with the top sheet of a pile, a sheet actuated pendulum for controlling the movement away from the pile, and means for varying the pressure exerted by said combing device, said means being adapted to be rendered inoperative by a sheet in a predetermined position.

12. In a sheet-feeding machine, a sheet-feeding instrumentality movable into and out of engagement with the top sheet of a pile under normally constant pressure, of means for applying additional pressure to said instrumentality, means normally holding said additional pressure means inoperative, and sheet controlled means for automatically releasing said holding means.

13. In a sheet feeding machine, a sheet-feeding instrumentality movable into and out of engagement with the top sheet of a pile under normally constant pressure, of means for applying additional pressure to said instrumentality, means normally holding said additional pressure means inoperative, and sheet controlled means for automatically releasing said holding means, said additional pressure means including a plunger under pressure tending to drive it against said instrumentality under the control of said holding means.

14. In a sheet-feeding machine, a sheet-feeding instrumentality movable into and out of engagement with the top sheet of a pile under normally constant pressure, a plunger under pressure suitably disposed to apply additional pressure to said instru-

mentality, a detent normally holding said plunger away from said instrumentality, and sheet-controlled means for releasing 65 said detent.

15. In a sheet-feeding machine, a sheet-feeding instrumentality movable into and out of engagement with the top sheet of a pile under normally constant pressure, a 70 plunger under pressure suitably disposed to apply additional pressure to said instrumentality, a detent normally holding said plunger away from said instrumentality, and sheet-controlled means for releasing 75 said detent, said sheet controlled means including a lever arm normally sustained in inoperative position by a sheet underneath it and adapted to become operative when a sheet is absent.

16. In a sheet feeding machine, a sheet-feeding instrumentality movable into and out of engagement with the top sheet of a pile under normally constant pressure, a plunger under pressure suitably disposed to 85 apply additional pressure to said instrumentality, a detent normally holding said plunger away from said instrumentality, and sheet-controlled means for releasing 90 said detent, said sheet-controlled means including a lever arm normally sustained in inoperative position by a sheet underneath it and adapted to become operative when a sheet is absent, said lever arm being provided with a cam arm, and a cam which 95 retains said sheet-controlled means inoperative during the movement of a preceding sheet from the pile.

17. In a sheet-feeding machine, a sheet-feeding instrumentality movable into and 100 out of engagement with the top sheet of a pile under normally constant pressure, a plunger under pressure suitably disposed to apply additional pressure to said instrumentality, a detent normally holding said 105 plunger away from said instrumentality, and sheet-controlled means for releasing said detent, said sheet-controlled means including a lever arm normally sustained in inoperative position by a sheet underneath 110 it and adapted to become operative when a sheet is absent, said lever arm being provided with a cam arm and a cam which retains said sheet controlled means inoperative during the movement of a preceding sheet from the pile, said cam being adapted 115 to release said cam arm immediately prior to the instant the sheet feeding instrumentality contacts with the pile.
